UNITED STATES PATENT OFFICE.

WARNER R. BUXTON, OF LONGMEADOW, MASSACHUSETTS, ASSIGNOR TO BUXTON,
INCORPORATED, A CORPORATION OF MASSACHUSETTS.

CASE FOR KEYS AND THE LIKE.

Application filed April 25, 1922. Serial No. 556,371.

To all whom it may concern:

Be it known that I, WARNER R. BUXTON, a citizen of the United States, residing at Longmeadow, in the county of Hampden and State of Massachusetts, have invented new and useful Improvements in Cases for Keys and the like, of which the following is a specification.

This invention relates to improvements in cases for keys and the like and the improvements are particularly applicable to that type of key case in which the key retaining members are pivotally supported from the case for swinging movement into and out of the latter along arc-like paths of fixed radius. An example of one of such type of key case is disclosed in my prior United States Letters Patent No. 1,261,692 granted April 2, 1918.

This invention is concerned generally with the simplification of the key case structure and the provision of a key case which may be manufactured at relatively low cost and nevertheless retain the desired qualities of durability, convenience in operation, and reliability in retaining the keys under the special conditions of service to which these key cases are subjected.

An object of this invention is to provide an improved hook, adapted for use in key cases or for other purposes, consisting of a one piece member having a shank portion at one end of which is a portion bent to form a partially open eye to be hooked over a pivotal support and at the other end of which is a portion bent backwardly upon the shank to form a retaining loop, the last named portion having a part which abuts the shank at a point closely adjacent said eye,—characterized in that such part functions to yieldably close the retaining loop and to also close said eye and prevent substantial radial movement of the hook on its pivotal support.

Another object of the invention is to provide a key case wherein the key retaining members are readily removable from their pivotal supporting means, when desired.

Another object of the invention is to provide a key case, with key retaining members of improved construction which may be rapidly and conveniently assembled in the case.

Another object of the invention is to pro-

vide in a key case an improved hook, which is so constructed as to retain the keys under all usual conditions of service to which the key case is subjected.

Other objects and advantages will appear in the following description and in the illustrative embodiment of the invention in the accompanying drawings, in which—

Figs. 1 and 2 are front elevational views of a key case embodying my invention and taken respectively, with the case in open and closed positions;

Fig. 3 is a similar view of the pivotal supporting means for the key retaining members;

Fig. 4 is an enlarged cross-sectional view showing, in full detail, one key retaining member and the manner in which it is supported from said means;

Fig. 5 is a similar view, illustrative of the manner in which such members are assembled on the aforesaid means; and

Fig. 6 is an elevational view showing a modification in the hook construction.

Referring to these drawings; the case proper may be variously constructed, as desired, so long as the key retaining members are permitted to swing into and out of the case, when the latter is open, and are held from such movement when the case is closed. Preferably, the case is constructed substantially as disclosed in my prior patent, above identified, and, accordingly, the case forming member consists of a strip of flexible material, such as leather or the like, which has a central portion 10, forming the back of the case, and two end portions 11, foldable along the lines 12 in overlapping relation over the back 10 and forming the flaps of the case. These flaps may be removably secured together in any suitable way, as by the interengageable male and female fasteners 13 and 14, respectively.

The key retaining members may be pivoted to the case to swing in the described manner in various ways and, as an example of one suitable way which is advantageous on the score of low manufacturing cost, I have shown a plate 15, which is suitably secured to back 10 near the upper edge thereof, as by eyelet rivets 16. This plate is provided, near its upper edge, with a longitudinal series of openings 17, pref-

erably, although not necessarily, in the form of slots having parallel side walls, as shown. Those portions 18 of the plate 15, between such openings and the adjacent edge of the plate, constitute pivotal supporting means for the key retaining members and upon such means the latter are pivotally engaged in a manner to be later pointed out in full detail. The parallel side walls of the openings 17 are desirable in that they parallel the sides of the key retaining members and may be located as closely adjacent thereto, as is feasible or desired, to limit the lateral movement of the members on their pivotal supporting means. The upper walls of openings 17, when parallel with the upper edge of plate 15, form a better pivotal support for the key retaining members by reason of the uniformity in width of the portions 18 thus afforded.

The hook of this invention, represented generally by reference letter *h*, consists of a one piece member which is bent up in the shape shown in Fig. 4. The hook has a back, shank or body portion 20, at one end of which a portion 21 is bent, preferably in circular form, to provide an eye 22, which is partially open, having an entrance opening 23. The shank 20, at its other end, has a portion 24 which is bent backwardly upon the shank to form a retaining loop 25. This portion 24 extends toward eye 22 and toward shank 20, preferably in generally converging relation with the latter, and at its free end has a portion, such as 26, which abuts the shank at a point closely adjacent eye 22 and forms a yieldable closure for loop 25. Such portion 26 also has a second function, which is to close the opening 23 to eye 22 and, not only to close this opening, but to close it in such a manner that the hook is restrained from any considerable freedom for radial movement relatively to its pivotal supporting means 18.

The portion 26 may be formed in various ways and need not necessarily be bent in outwardly diverging relation to the hook shank 20, as shown, although this arrangement has generally been found preferable. For example, the free end of the portion 24 might be bent inwardly, preferably in curved form, as shown at 27 in Fig. 6, and still function in the manner described. The material, of which the hooks are made, should, of course, have sufficient resiliency to permit the portions 24 and 26 to be deflected away from shank 20, for the purpose of permitting insertion and removal of the keys in loop 25 and insertion and removal of the hooks from their pivotal supporting means, and yet spring back into their normal illustrated positions.

Preferably the upper portion of plate 15 is offset for the purpose of throwing the

portions 18 away from back 10 and forming a recess therebetween to receive the back portions of the parts 21 and prevent them from bulging out the back. Thus, the upper portion of plate 15 may be bent in the 70 curved form shown at 30 in Fig. 4.

The special usefulness of a hook of this character in a key case of the general type described is in the convenience and rapidity with which the hooks may be assembled on 75 their pivotal supporting means. To assemble a hook on the latter, the hook is positioned, relatively to the plate 15, substantially as shown in Fig. 5 and then pushed downwardly over the portion 18 of the 80 plate,—the portion 26 of the hook yielding away from the free end of portion 21 to receive the portion 18 and allow the hook to be moved relatively thereto until the entrance 23 to eye 22 comes in line with the 85 portion 18. The portion 26 and the free end of portion 21 preferably cooperate to form a converging entrance to facilitate the operation described. When portion 18 is positioned in line with entrance 23, the free end 90 of portion 21 is in line with a slot 17 and the hook can then be swung (counter-clockwise as shown) to cause portion 21 to enter the slot, whereupon eye 22 is engaged with the portion 18 and the entrance 23 is then 95 closed by the portion 26 springing back into its original position. The hooks may be removed by a reversal of the operation described.

This feature of the invention is especially 100 important as making for lessened cost of manufacture and permitting a practically and commercially satisfactory key case to be marketed at relatively low price. To provide a really satisfactory key case, the 105 hooks should be made of spring metal. This means that the metal must be bent to the desired form and then subjected to the heat treatment necessary to give the desired spring action. Bending of the hooks, after 110 they have been so treated, to an extent such as to give a permanent set to the material is not feasible and therefore, in key cases having proper spring hooks, the hooks need to be assembled on their supporting plate 115 through the intermediary of a rod, or some equivalent expedient resorted to to connect the hooks without any material bending thereof. Key cases, lacking this expedient, have been provided heretofore and the eyes 120 of the hooks have been left partially open and then closed down after assembly by bending the metal but naturally, in order to permit bending of the metal to close the eye, the spring quality of the key retaining 125 hooks has had to be sacrificed and such hooks do not stand up satisfactorily in service. The present hook requires no bending, to a degree sufficient to give a permanent set in the metal, and can be manufactured 130

of proper material and properly treated to give the desired spring action, nearly as cheaply as the usual hook. Its construction, however, is such that it may readily be assembled on an apertured plate and far more readily than has been customary heretofore, where each hook had to be bent down after assembly to close the eye. Naturally, the rod and lugs heretofore used on the plate 10 may be dispensed with and a considerable saving in manufacturing cost made as well as a substantial saving in the cost of assembling the hooks, which latter cost is usually the large item.

15 The removability of the hooks from the key case is likewise desirable. It may be that a person having a large number of keys, does not care to carry them all at one time. In such cases, the person may have 20 spare hooks with keys upon them, which hooks may be substituted for others in the key case when these particular keys need to be carried. Also, a person may wish to loan a certain group of keys, say the keys to his 25 automobile, and these keys grouped on a single hook, may be extracted from the case by removing the hook, thereby retaining the group of keys together.

The hook is also characterized in that the 30 entrance to loop 25 is at the apex thereof and remote from the base. This feature is particularly useful in hooks for key cases on account of special conditions encountered in use. In using the key case, a hook with the 35 key thereon is swung out of the case and the key is turned in the lock while the case is held stationary in the hand. The hook, being attached to the case, cannot turn with the key and the result is a side strain on 40 the retaining loop which strain, if imposed on snap hooks of ordinary type, having a break near the base of the loop, separates the mating ends of the hook and sometimes permits escape of the key from the hook. 45 With the present hook such side strains do not open up the loop, or at least, do not open it up at such a location or in such a manner as to permit escape of the keys.

The invention has been disclosed herein 50 in an embodiment at present preferred, for illustrative purposes, but the scope of the invention is defined by the appended claims rather than by the foregoing description.

What I claim is—

55 1. In a key case, of the type wherein the key retaining members are pivotally supported from the case for swinging movement into and out of the latter along arc-like paths of fixed radius, means provided 60 on the case affording a pivotal support, and key retaining members pivotally mounted on the latter, each of said members having a key retaining loop and also having an open eye to be hooked over said support and 65 means affording a spring closure for said

eye to retain the member on said support and partition said eye from said loop.

2. In a key case, of the type wherein the key retaining members are pivotally supported from the case for swinging movement into and out of the latter along arc-like paths of fixed radius, means provided on the case affording a pivotal support, and key retaining members pivotally mounted on the latter, each of said members having a 70 key retaining loop with a yieldable portion forming a closure therefor and an open eye for engagement with said support, the said yieldable closure forming portion also yieldably closing the otherwise open eye. 80

3. In a key case, of the type wherein the key retaining members are pivotally supported from the case for swinging movement into and out of the latter along arc-like paths of constant radius, means provided on the case affording a pivotal support for said members, and key retaining members, each thereof comprising a back portion one end of which is bent to form an open eye for engagement with said support 85 and the other end of which is bent backwardly upon the back to form a key retaining loop and terminates with a portion forming a closure for the loop and a closure for said eye. 90

4. In a key case, of the type wherein the key retaining members are pivotally supported from the case for swinging movement into and out of the latter along arc-like paths of constant radius, means provided on the case affording a pivotal support for said members, and key retaining members, each thereof comprising a back portion one end of which is bent to form an open eye for engagement with said support and the other end of which is bent backwardly upon the back and extends in converging relation toward and into engagement with the latter to form a key retaining loop and terminates with a portion diverging from the back and closing the open portion of said eye. 100 105 110

5. In a key case, of the type wherein the key retaining members are pivotally supported from the case for swinging movement into and out of the latter along arc-like paths of constant radius, a member provided on the case and having a longitudinal series of openings near one edge thereof, and key retaining members, each thereof comprising a back portion one end of which is bent to form an open eye for insertion in one of said openings and adapted to be hooked over that portion of said last named member between said openings and said edge and the other end of which is bent backwardly upon the back and extends in converging relation toward the latter to form a key retaining loop and terminates with a portion forming a closure for the loop and a closure for said eye. 115 120 125 130

6. A hook, comprising a one-piece member, bent to form a shank, and a partially open eye at one end of the shank, and a portion at the other end of the shank bent backwardly thereupon to form a retaining loop, the free end of the last named portion having a part which abuts the shank at a

point closely adjacent said eye to form a closure for said loop and which also closes the opening in said eye.

10

In testimony whereof I have affixed my signature.

WARNER R. BUXTON.
